UNITED STATES PATENT OFFICE.

DAVID EDWARD TURNER, OF LONDON, ENGLAND.

TIP-UP AND LIKE CHAIR.

Application filed June 9, 1924, Serial No. 718,920, and in Great Britain October 17, 1923.

This invention relates to tip-up and like chairs and has for its object to provide improved means which, while complying with municipal requirements, automatically acts to tip the seat into the up position when the seat is not in use.

According to the present invention the operating part of the tip-up mechanism is associated with a side standard or upright or 10 with an adjacent part of the seat. The seat is adapted to be supported by and between standards or uprights, one upright or standard being provided with means which is placed under compression when the seat 15 is lowered and which, when the seat is freed from the load automatically acts to tip the seat into the up position. An upright or standard is provided with a hollow drum or casing as an integral or detachable portion 20 thereof. The hollow drum or casing is provided with an interrupted circular recess to contain a helical spring one end of which abuts against the end of the said recess, the other end of the spring being arranged to 25 abut against a stop or projection provided on a disc which may be suitably attached to or form an integral part of the seat. The said disc may be provided with a further projection which may be arranged to co- 30 operate with a suitable projection in the interior of the hollow drum or casing so as to retain the seat in the down position. The outer projection on the aforesaid disc when the seat is lowered acts on the resilient member and compresses the latter. When the 35 seat is relieved of pressure or load the spring automatically acts on the said projection on the disc and tips the seat into the up position. If so desired the outer 40 face of the hollow drum or casing may be provided with a stop on which the adjacent seat bears or rests when in the down position. Further, the opposite standard may be provided with a stop or projection to co- 45 operate with the stop or projection on the outer face of the hollow drum or casing so that the seat may be supported when in the down position by both stops.

In order that the invention may be clearly understood reference is made to the accompanying drawing which shews by way of example a construction of tip-up or like chair in accordance with the present invention.

Figure 1 is a side view of part of a tip-up

and like chair in accordance with the present invention.

Figure 2 is a front view.

Figure 3 is an interior view of the hollow drum or casing hereinafter fully described, 60 and Figure 4 is an elevation of the disc which is attachable to and detachable from the seat itself, the said elevation shewing the inner face of the disc.

In the general arrangement of the parts 65 shewn in Figures 1 and 2 the standards or uprights are indicated at 1, 2. The hollow drum or casing is shewn at 3 and the seat is shewn at 4. The hollow drum or casing is provided with a circular recess 5 to contain a helical spring 6 one end 7 of which abuts against the wall 8 of the circular recess, the other end 9 of the spring abutting against a projection 10 on a disc 11 which is attachable to and detachable from the seat 70 4. If desired the disc 11 may be formed as an integral portion of the frame of the seat 4. The interior of the hollow drum or casing is provided with a stop 12 which co-operates with a projection 13 to support the 75 seat when in the lowered position. The seat may be supported on a spindle or plate 14 passing through the disc and also through the hollow drum or casing, the other end 15 of the spindle being supported by the hollow 80 drum or casing and, if so desired, in a bearing secured to the adjacent seat. The outer face of the hollow drum or casing may be provided with a projection 16 which in conjunction with a projection 17 on the opposite 85 standard acts to support the seat 4 when in the down position. If so desired the projections 12 and 13 in the hollow drum or casing and the disc 11 respectively may be omitted and the projections 16, 17 used instead or, if so desired, both sets of projections 90 95 may be used.

The action of the device is as follows, it being assumed that the disc 11 is rigidly secured to or forms an integral part of the 100 seat 4. When the seat is tipped down the projection 10 which abuts against the end 9 of the spring compresses the spring 6 against the bottom 8 of the circular recess 5. On releasing the seat the spring 6 acts on the 105 projection 10 on the disc 11 and rotates the disc and consequently the seat 4 which is thus tipped or rotated on its spindle or with its spindle into the up position.

It is of course to be understood that while 110

the casing is shown on the standard and the disc on the seat, the reverse arrangement without change in the detailed structure is within the spirit of the invention.

5. What I claim is:—

1. A tip-up chair including a pair of spaced standards, a seat supported by and between the standards, a casing mounted on one of the standards and disposed approximately midway of the front and back of the standard with which the casing is associated, a helical spring arranged in the said casing, a projection carried by the seat and adapted to move therewith so as to engage and effect shortening of the length of the spring as a whole and as the seat is lowered, a second projection carried by the seat, and means carried by the casing to be engaged by said second projection to limit movement of the seat when being lowered.
2. A tip-up chair including a pair of spaced standards, a seat supported by and between the standards, a casing mounted on one of the standards and forming an integral portion thereof, an arcuate recess provided in said casing and a helical spring inserted into the said recess, a projection carried by the seat and adapted to engage and reduce the length of the helical spring as the seat is lowered, said recess having an abutment to be engaged by said projection to limit movement of the seat as the latter is raised by the spring, and cooperating means on the casing and seat to limit the movement of the seat as it is being lowered.
3. A tip-up chair comprising a pair of spaced standards, a seat supported by and between the said standards, a casing integral with one of the said standards and provided in its interior with a projection, a helical spring inserted in an arcuate recess in the said casing and having one of its ends abut-

ting against a portion extending radially across the said recess, a disc carried by the seat, a projection on the said disc adapted to engage the free end of the helical spring and to reduce the length thereof as a whole on the seat being lowered, a second projection on the said disc adapted to cooperate with the interior stop in the said casing so as to limit the downward movement of the seat.

4. A tip-up chair comprising relatively movable elements as a standard and a seat, a casing mounted on one of the elements and formed with an annular channel and with a stop inwardly of the channel, a helical spring seated in the channel, a disc carried by the other of said elements and having a projection to bear against one end of the spring and longitudinally compress the same in the relative movements of the elements, said disc having an additional projection to cooperate with the stop on the casing to limit relative movement of the elements.

5. A tip-up chair comprising relatively movable elements as a standard and a seat, a casing mounted in one of the elements and formed with an interrupted annular channel having a fixed terminal abutment, a helical spring housed in the channel with one end bearing against the abutment, a disc carried by the other of said elements, said elements cooperating for relative rotary movement, means carried by the disc to seat in said channel and bear against one end of the spring to longitudinally compress the same in the relative rotary movements of the elements, and cooperating means on the disc and casing to limit the relative rotary movements of these elements in one direction.

In testimony whereof I have hereunto signed my name.

DAVID EDWARD TURNER.
